UNITED STATES PATENT OFFICE.

NIELS WALTERSEN AASEN, OF CHRISTIANIA, NORWAY.

BREATH DEFLECTOR.

Application filed May 25, 1923. Serial No. 641,467.

To all whom it may concern:

Be it known that I, NIELS WALTERSEN AASEN, Storgaten 26, Christiania, Norway, have invented certain new and useful Im-
5 provements in Breath Deflectors; and I do hereby declare the following to be a full, clear, and exact description of the invention, such as will enable others skilled in the art to which it appertains to make and
10 use the same, reference being had to the accompanying drawings, and to letters or figures of reference marked thereon, which form a part of this specification.

The object of my invention is an apparatus conducting the warm respiration air to parts of the head where these warm currents of air have proved to have a somniferous effect probably from their action on certain nerve centers.

20 The invention shall in the following be specified with reference to the accompanying drawings, in which Fig. 1 is a vertical section through an executional form of the apparatus, Fig. 2 a front view of the same
25 and Fig. 3 a top view of the same.

The apparatus may suitably have the form of a masklike device 1 made of paper, cardboard, celluloid or any other suitable material. The edge of this device is provided with a rim 2 of felt, cotton or any other soft material, said rim serving to tighten the mask against the cheek and chin in order that the respiration air shall not pass away along the sides of the mask.

30 In its top part the apparatus is suitably provided with a narrow inturned part 3 adapted to be supported by the part of the forehead lying direct above the root of the nose.

35 The mask has at its upper portion a bridge form, divided by the inturned portion 3 providing an open vaulted passage 4 passing past each eye through which passages the respiration air is conducted past the eyes, the eyebrows and the forehead and temples.

The mask may preferably be provided with an automatically acting valve or flap 5 of any suitable construction, said valve or flap opening for inhalation but closing for exhalation. Such valve or flap may for instance be made from a piece of silk or other fabric covering an aperture in the mask but opening more or less for inhalations.

It will be understood that the apparatus

acts in such away, that fresh air is inhaled through the valve or flap 5 and the warm exhalation air will be conducted through the passages 4 past the eyes and the adjoining parts of the forehead and temples. The intermitting warm currents of air brushing in this way past the eyes and forehead has, as before mentioned, proved to have a somniferous effect.

60 The keeping on of this apparatus during the sleep is not inconvenient. According to experiments made by the applicant, the apparatus will also be efficient for the said purpose, when the valve or flap 5 is dispensed with, both inhalation and exhalation passing then through the passages 4. It is, however, preferable to use an inhalation valve in order to avoid the deposition of moisture within the mask.

65 The invention is not limited to the specific form of the apparatus illustrated in the drawings. It may for instance only cover nose and mouth and the warm exhalation air may be carried up to the forehead, temples or other parts of the head, where warm currents of air have a somniferous effect, by aid of pliable tubes or the like.

Claims:

1. A somniferous device, comprising a mask adapted to be secured to the face and extending substantially from the chin to the forehead, and having means for providing a substantially air-tight fit against the cheeks and chin, and an arched portion 80 for spacing the upper portion of the mask from the forehead, whereby when said mask is adjusted the relatively warm exhaled air will be confined and directed upwardly past the eyes and forehead.

85 2. A somniferous device, comprising a mask adapted to be secured to the face and extending substantially from the chin to the forehead, a rim of resilient material formed around the sides and bottom of said mask 90 for providing an air-tight fit against the cheeks and chin, a bridge at the upper portion of the mask for spacing said upper portion from the forehead and an inturned portion dividing the same into two passages, whereby when said mask is so adjusted the relatively warm exhaled air will be confined and directed upwardly past each eye and the adjoining parts of the forehead.

100 3. A somniferous device, comprising a mask adapted to be secured to the face and extending substantially from the chin

to the forehead, a rim of resilient material formed around the sides and bottom of said mask for providing an air-tight fit against the cheeks and chin, a bridge at the upper portion of the mask for spacing said upper portion from the forehead and an inturned portion dividing the same into two passages, and a valve in the lower portion of the mask adapted to open upon inhalation and close against exhalation, whereby when said mask is adjusted the relatively warm ex-

haled air will be confined and directed upwardly past each eye and the adjoining parts of the forehead.

In testimony that I claim the foregoing ¹⁵ as my invention, I have signed my name in presence of two subscribing witnesses.

NIELS WALTERSEN AASEN.
